UNITED STATES PATENT OFFICE

HOMER W. JONES, OF NEWARK, NEW JERSEY, ASSIGNOR TO NATIONAL CARBON COMPANY, INC., A CORPORATION OF NEW YORK

ADJUSTABLE LAMP SOCKET

Application filed May 22, 1928. Serial No. 279,761.

This invention relates to flashlights, battery hand lamps, and the like, and more specifically to means whereby the lamp in such a device may be adjusted so its filament is on the optical axis of an associated reflector.

Flashlights comprising means for securing relative axial movement between the lamp and reflector to focalize the light are well known in the art, but the result obtained from this focalizing movement is frequently unsatisfactory because many of the lamp filaments, due to manufacturing tolerances, are not on the axes of the lamps so, regardless of the quality of the flashlights, many of the lamp filaments cannot be brought to the focal point of their associated reflectors by this movement alone. Therefore, the desired concentration and intensity of the light beam cannot be secured.

One of the objects of this invention is an improved lamp socket constructed so the lamp therein may be moved laterally to position its filament on the optical axis of an associated reflector. Other aims and objects will be apparent from the description and illustration of the invention.

I attain these objects by means of the apparatus shown in the accompanying drawing in which:

Fig. 1, is a longitudinal sectional view of a focusing flashlight embodying my invention,

Fig. 2, is an enlarged view in elevation of my improved lamp holder, and

Fig. 3, is a longitudinal sectional view of another type of focusing flashlight embodying my invention.

In the drawing 10 is a conventional tubular casing of metal or other material. Within the upper end of the casing 10 is a support or diaphragm 11 which is held in place by a spring ring 12. The support 11 is preferably of insulating material such as fiber but other materials may be used and it may be held in the casing 10 by other means well known in the art. Threaded upon the upper end of the casing 10 is a head 13 that may be adjusted on the casing by screwing it either up or down for a purpose that will be described later. Within the head 13 is a reflector 14 that rests upon the upper end of the head 13

and is held in place by the bezel 15 that is threaded to the head 13 and also carries the cover glass 16. Within the casing 10 is the usual battery 17 of dry cells, and threaded to the lower end of the casing 10 is the usual bottom cap 18 carrying the battery supporting and contacting spring 19. Mounted upon the outside of the casing 10 is a conventional switch 20 for closing and opening the circuit through the battery and lamp.

Mounted on the upper side of the support 11 is a lamp holder 21. This lamp holder may be of any suitable material but I prefer to form it from a single piece of conductive metal such as brass or bronze. The lamp holder 21 has a threaded socket portion 22 that receives and supports the lamp 23 in operative relation to the reflector 14. Extending outwardly from the lower end of the lamp holder 21 is a base portion 24 that is attached to the support 11 by a plurality of rivets of which one is shown at 25. Between the threaded socket portion 22 and the base portion 24 of the lamp holder 21 is an unthreaded portion 26, herein termed a connecting portion. A short section of both the right and left sides of this connecting portion 26 is removed by cutting a transverse slot 30 in each side, so the socket portion 22 is supported at this point by only a narrow section 27 of the annular wall 26 at the front of the lamp holder and by a similar section of the annular wall 26 at the back of the lamp holder. Also, just above the slots 30, a short section of both the front and back sides of the connecting portion 26 is removed by cutting a transverse slot 31 in each side, so the socket portion 22 is supported at this point by only a narrow section 28 of the annular wall 26 at the right side of the lamp holder and by a similar section of the annular wall 26 at the left side of the lamp holder. These supporting parts 27 and 28 are of sufficient strength to support the socket portion 22 and the lamp 23 during service conditions and they are also sufficiently pliable to bend under manual pressure so the lamp may be moved laterally to center its filament optically in the reflector. Therefore, when a new lamp is inserted in the flashlight, if the fila-

ment is not in the desired position at the axis of the reflector, the lamp and the socket portion 22 of the lamp holder 21 may be manually moved in a lateral direction to bring the filament and the optical axis of the reflector into coincidence. When the lamp is moved forward or backward the pliable connecting portions 28 are bent, and when the lamp is moved to the right or left the pliable supporting parts 27 are bent. By various combinations of these movements the lamp socket and the lamp therein may be set in any other position, and the socket will remain set in the proper position for any particular lamp, but may again be readily adjusted to some other position for a replacement lamp that has its filament in a different position. A resilient conductor 32 is secured to the center of the support 11 by a rivet 33 so they conduct current from the central terminal of the battery 17 to the central terminal of the lamp 23, and an insulated conductor strip 34 connects the switch 20 with the base 24 of the lamp holder 21.

When the switch 20 is in closed position the path of the current through the flashlight is as follows: from the positive terminal of the battery 17 to the rivet 33, conductor 32, lamp 23, lamp holder 21, conductor strip 34, switch 20, casing 10, bottom cap 18, and battery supporting spring 19, to the negative terminal of the battery 17. The reflector may be moved axially of the lamp to focalize the light by screwing the head 13 either up or down on the casing 10. If necessary to obtain a focus the head 13 may be removed by unscrewing it from the casing 10 and the lamp 23 may be moved laterally by pushing it with the thumb or finger to position the lamp filament at the optical axis of the reflector. When the head 13 is replaced, if it is found from an inspection of the reflected light beam that the filament is still not at the optical axis of the reflector, a second or third adjustment is usually sufficient to secure the desired result. After the lamp filament has been optically centered in the reflector the concentration of the reflected light beam may be controlled by the axial movement of the reflector and no further lateral movement is usually necessary until a new lamp is placed in the flashlight.

The form of the lamp holder 21 may be varied to adapt it for use with flashlights constructed differently from that shown in Fig. 1. For example, Fig. 3 shows my improved form of lamp holder adapted to a flashlight wherein the focalizing movement is secured by adjusting the bottom cap 18 on the casing 10. Secured to the under side of the support 11 by a suitable number of rivets 25 is a casing 35. Sliding within the casing 35 is a sleeve 36 having an inturned flange 37 at its lower end to which is attached my improved lamp holder 21 which extends up-

wardly through the sleeve 36, casing 35, and support 11, and supports the lamp bulb 23 in operative relation to the reflector 14. Carried by the sleeve 36 but insulated therefrom and also from the lamp holder 21 is a resilient conductor 32 that connects the central terminal of the lamp 23 to the central terminal of the battery 17. Within the casing 35 and sleeve 36 is a retractile spring 38 that rests against the under side of the support 11 and presses the sleeve 36 and the parts attached thereto downward so that conductor 32 is held against the upper terminal of the battery 17. Within the bottom cap 18 is a rigid battery support 39 upon which the battery 17 rests. The usual conductor strip 34 connects the switch 20 to the casing 10.

When the switch 20 is in closed circuit position the path of the current through the flashlight is from the upper terminal of the battery 17 to the conductor 32, lamp 23, lamp holder 21, sleeve 36, casing 35, conductor strip 34, switch 20, casing 10, bottom cap 18, and battery support 39 to the battery 17. To focalize the light the bottom cap 18 is adjusted on the casing 10 thereby moving the battery support 39, battery 17, conductor 32, sleeve 36, lamp holder 21 and lamp 23, relatively of the reflector 14. The retractile spring 38 holds the sleeve 36 and the parts carried thereby against the battery 17 and the battery 17 against the battery support 39 so that the parts move as a unit in response to the movement of the end cap 18 and the battery support 39.

The bezel 15, cover glass 16, and if desired the reflector 14, may be removed from the casing 10 and the lamp bulb moved laterally to centralize the lamp filament in the reflector 14 as described in connection with Fig. 1. This adjustment is made in the same way in both of the types of flashlights shown in Figs. 1 and 3.

The form of the lamp holder may be varied to adapt it to other types of lamps and lamp bulbs without departing from the spirit of the invention or sacrificing any of the rights thereunder.

I claim:

1. In a flashlight, a reflector, a lamp bulb in operative relation thereto, and a lamp holder for said lamp comprising a socket and a base joined by a plurality of pliable portions adapted for being manually bent in pairs during use to provide relative movement between said socket and said base to align said lamp and reflector.

2. In a flashlight, a lamp holder comprising a socket and a base joined by a plurality of pliable portions adapted for being bent in pairs to provide relative movement between said base and said socket, one pair of said pliable portions being adapted for providing movement in different directions from those provided by the other pair.

3. In a flashlight, a lamp holder comprising a socket, a base, opposed pliable portions adapted for providing relative movement between said socket and said base in two directions, and opposed pliable portions adapted for providing relative movement between said socket and said base in two directions different from those provided by said first mentioned pliable portions.

10 4. In a flashlight, an annular lamp holder comprising a socket, a base, two pliable portions in transverse alignment, and two pliable portions in transverse alignment at substantially right angle to the first two.

15 5. In a flashlight, a tubular metal lamp holder comprising a threaded socket, a flanged base, a pair of pliable portions adapted for being bent in two directions, and a pair of pliable portions adapted for being bent in two directions different from the first pair, said pairs of pliable portions being in different planes along the axis of said lamp holder.

20 6. In a flashlight, a tubular metal lamp holder comprising a threaded socket, a flanged base, and a connecting section therebetween having the front and back removed to form a pliable portion at each side, and each side removed in a different plane to form a pliable portion at both the front and back, said pliable portions being adapted for being bent to provide relative movement between said socket and said base.

25 7. In a flashlight, a unitary tubular metal lamp holder comprising a threaded socket; a flanged base; and a plurality of pliable portions therebetween symmetrically arranged so part of said pliable portions are adapted for being bent to provide relative movement between said holder and said base in two directions, and the rest of said pliable portions are adapted for being bent to provide relative movement between said holder and said base in two directions different from the first two, and all of said pliable portions are adapted for being bent to provide relative movement between said holder and said base in other directions.

In testimony whereof, I affix my signature.
HOMER W. JONES.
